(**) Term: **14 Years**

(57) **CLAIM**

(21) Appl. No.: **29/137,945**

The ornamental design for an electronic image data input/output apparatus, as shown and described.

(22) Filed: **Mar. 5, 2001**

DESCRIPTION

(30) **Foreign Application Priority Data**

Sep. 6, 2000 (JP) 2000-024838

FIG. 1 is a front view of an electronic image data input/output apparatus showing my new design;

(51) LOC (7) Cl. **14-02**

FIG. 2 is a rear view thereof;

(52) U.S. Cl. **D14/349**

FIG. 3 is a top plan view thereof;

(58) **Field of Search** D14/349, 351,

FIG. 4 is a bottom plan view thereof;

D14/352, 300, 311, 240, 301, 356; D13/162,

FIG. 5 is a left side view thereof;

184, 199; D6/432, 436, 445, 448; 312/223.1-223.3,

FIG. 6 is a right side view thereof; and,

194; 360/99.01-99.12; 369/34, 36; 361/690-696

FIG. 7 is a perspective view thereof.
